UNITED STATES PATENT OFFICE.

JACOB GERRITSON, OF KANKAKEE, ILLINOIS, ASSIGNOR TO PARAMOUNT HOSIERY FORM DRYING CO., OF CHICAGO, ILLINOIS, A CORPORATION OF ILLINOIS.

HOSIERY DRYING AND SHAPING STRUCTURE.

1,320,753.

Specification of Letters Patent.

Patented Nov. 4, 1919.

Application filed December 18, 1918. Serial No. 267,344.

To all whom it may concern:

Be it known that I, JACOB GERRITSON, citizen of the United States of America, residing at Kankakee, in the county of Kankakee and State of Illinois, have invented certain new and useful Improvements in Hosiery Drying and Shaping Structures, of which the following is a specification, reference being had therein to the accompanying drawing.

This invention relates broadly to hosiery drying and shaping structures, and more specifically to a fabric-holding device which is attachable thereto for preventing the natural shrinking or creeping of hosiery after being placed upon the drying structure and while the moisture therein is being evaporated therefrom.

The present invention involves an improvement upon and an advance over the particular device disclosed in U. S. Letters-Patent 1,279,332, granted September 17, 1918, to L. F. Gray, L. Wedge and E. Giese. The structure of that patent has, in practical use, been found to be exceedingly useful and efficient; but it has been discovered, in attaching the pile-including fabric by silicate of soda (as a binder) to a heated form, that this substance tends to affect the texture of the fabric and thereby reduces its serviceability. The present invention is predicated upon the recognition by me that it is desirable—in fact rather necessary—to treat the fabric itself (in a manner to be explained hereafter) before applying it to the form; and, in addition, to interpose a separating element or structure between the fabric and the form, this separating structure constituting, also, an efficient support for the fabric and also a binding-instrumentality between the fabric and the form.

As a result of considerable experimentation, I have found that if the fabric is treated with some substance—such as a sizing made, say, from a flour paste or fluid—and if one or more backing sheets or pieces of material—such as asbestos paper, also similarly sized—are employed, and if, then, the backing sheets and fabric be attached to the form—preferably while the latter is in a heated condition—with a cementitious substance—such as liquid-glass (silicate of soda) or a mass which includes (in major or minor proportions) silicate of soda—the device thus constituted may be most securely

attached to the form, the securement being as nearly permanent as need be. The whole structure (including the several specified elements) is not only rendered highly efficient as a fabric-holding device, but becomes one which will endure for a considerable period. It is to be understood that the selection of the particular fabric is more or less dependent upon the proposed conditions of use; but, as I am at present advised, it is to be understood that a fabric which includes a base or body portion and a pile that has a tendency to lie down flat when brushed or rubbed in one way but which will stand out at an angle from the body-portion and present a multitude of fabric-gripping fingers or points when brushed or rubbed in the opposite direction, may be best adapted for the purpose in mind. Again, the separating or backing instrumentalities upon which the fabric is mounted may be of any appropriate material, shape and dimensions; but, as the drying-form upon which the holding-structure is mounted becomes considerably heated in use, a material which includes asbestos is very desirable and efficient. A material which is conveniently manufactured, procured and applied, and one well adapted for the purpose, is a so-called "fire and damp-proof asbestos paper," of suitable thickness and dimensions. The number of layers of the paper is, perhaps, largely one of choice, so long as these do not act as a heat-insulator; but, if the sheets of paper are formed and aggrouped in the manner hereinafter explained, two of these sheets will be found sufficient and, besides, each of these functions in a novel and desirable manner. The cementitious mass by which the structure is secured to the form may be any appropriate adhesive; but, I have found that a cement which is composed of or which includes silicate of soda (liquid-glass) especially is well adapted for the purpose. For ordinary purposes, commercial liquid-glass will suffice; but I have, myself, also devised an exceedingly efficient binder in the form of a cementitious mass which preferably includes silicate of soda, and it is to be understood that the term "cementitious mass," where herein specified, refers to either of these adhesives as well as any other suitable for the end in view.

In order that the invention may readily

be comprehended, both as to its construction and as to the manner of its application to drying and shaping forms, I have, in the accompanying drawings, illustrated various types thereof; and it is to be understood that these are merely illustrative and that such types as are here shown are susceptible of a wide range of modification and variation without departing from the spirit of the invention or sacrificing any of its salient features and underlying principles.

In the drawings:

Figure 1 is a view in elevation of a hosiery drying and shaping form with my improved fabric-holding device mounted thereon;

Fig. 2 is a fragmentary view in edge elevation of the same;

Fig. 3 is a view, on a larger scale, in transverse section on the line 3—3, Fig. 2;

Fig. 4 is a fragmentary sectional view, also on an enlarged scale, of a portion of the form with the fabric-holding device applied thereto;

Fig. 5 is a view similar to Fig. 4, with a portion of a stocking mounted on the form, and showing the holding action of my device, whereby shrinking or creeping of the stocking on the form is efficiently prevented while the form is effecting a drying and shaping of the stocking;

Fig. 6 is a view similar to Fig. 1, of a half-hose form, with my device applied thereto and a half-hose thereon;

Fig. 7 is a detached view of the base or form-attaching member;

Fig. 8 is a similar view of the interposed backing or fabric-distending member;

Fig. 9 is a view in rear elevation of the structure, showing the relative position of the ends of the fabric in respect to the ends of the base or form-attaching member;

Fig. 10 is a detached view of the fabric-member; and

Figs. 11 to 16 are views in elevation and section, respectively, of various modifications of the structure.

In these drawings, the reference-numeral 1 designates a so-called "Paramount" hosiery drying and shaping form as constructed and exploited under U. S. Patent No. 1,207,496, granted December 5, 1916. This form is hollow to contain a heating medium whereby heat is thereby applied to the internal surface of the fabric of the hosiery, designated generally by the reference-numeral 2. This form has fabric-smoothing and flattening sides 3 which, in this instance, are shown as arc-shaped and as merging into reduced or crease-forming edges 4. The form, itself, is provided with a base 5 by which it is mounted upon a pipe 6 for conducting a suitable thermal fluid to the interior of the form from a suitable source of supply.

Mounted on opposite sides of this form, and at a suitable or predetermined distance from the base 5, is my fabric-holding device 7, each of these being, preferably and as shown, of less width than that of the form 1 in order that the oppositely-disposed devices shall not entirely encompass the form. The longitudinal dimensions of each device are dictated by the amount of fabric-engaging surface which is to be presented to the hosiery, this being, in a large measure, dependent upon the character of the goods being treated. Some fabrics have a greater tendency to shrink while drying than others, and the amount of moisture in the fabric varies in different mills, since some manufacturers find it desirable or preferable to extract less moisture, (by the whizzer) than others. On the other hand, some hosiery fabrics—such, for instance, as woolen goods—hold their moisture in greater quantity than others.

The preferred type of device is shown, as a complete embodiment, in Figs. 1 to 6 and 9, and usually includes three instrumentalities, respectively, 8, 9 and 10, in connection with a binder by which the device is secured to the form 1. One of these devices is what I shall herein refer to as a base or form-attaching member 8, the dimensions of which are greater, both as to width and length, than the other two. This base-member is provided, adjacent its end, with two elongated slits or slots 11, of suitable length. The member is preferably a sheet of fire and damp-proof asbestos paper which has been treated on one side only with a suitable sizing or similar substance, this sizing being, for instance, of a liquid or pasty flour composition.

The second (9) of these three instrumentalities, aforementioned, is a piece or strip of fabric composed of a base or body portion 12 and a pile 13 which, in the present instance, is of a character to smooth down flat when rubbed in one direction but which, when rubbed in the other direction, tends to stiffen, stand out, and offer more or less reaction or resistance. The particular type of fabric, as thus described, is known in the art as panne plush. This instrumentality, during the "boarding" operation, permits the hosiery to be placed on the form without difficulty or discernible friction. But, the moment that the down-stretching motion on the hosiery (during the "boarding" operation) ceases, the pile 13 effectually engages the fabric and prevents it from shrinking or creeping upwardly so that, as the hosiery drying form tends to dry and shape the article, my improved hosiery-holding device efficiently retains it in its stretched condition until the fabric of the hosiery is set and given a "fixed" condition. This fabric instrumentality 9 is of less

width than the member 8, as shown, and has its opposite ends extended through the slits or slots 11 and disposed against the under-side of the member 8 so as to underlie the same. Only the side of the fabric which faces the member 8 is preferably treated to the sizing-compound, already referred to. If desired, the portions of the fabric which underlie the ends of the member 8 may be 10 trimmed or reduced in thickness, as by removing the pile from the portions of the member 9 which underlie the member 8.

Interposed between the members or instrumentalities 8 and 9, is the backing or 15 fabric-distending member 10. Preferably, this member is of approximately the same width as the fabric member 9, and of a length approximating the distance between the two slits or slots 11 in the member 8. 20 This member 10 tends to distend or raise the fabric-member 9 into a plane above that of the outer surface of the member 8. Hence, as shown in Figs. 2, 4 and 5, for instance, the fabric member 9 occupies a plane considerably removed from that of the member 25 8 and is thus caused to perform its fabric gripping and holding action in a more efficient manner; the member 8 being, then, out of interfering position with the hosiery 30 as it is being boarded. The member 8 is preferably of the asbestos-paper type described with reference to the member 8; but it is preferably sized on both sides so that its sized surfaces will be presented both 35 to the sized surface of the base-portion 12 of the member 9 and also to the sized surface of the paper-member 8.

These three components or instrumentalities 8, 9 and 10, are bound together—to constitute an article of commerce—by a cementitious substance suitable for the purpose. The object of sizing one (the inner) surface of the fabric-member 9, both surfaces of the paper-member 10, and one (the outer) surface 45 of the paper-member 8 is in order that the cementitious binder may more effectively cement these three instrumentalities together; it having been found in my experiments that the sizing on the contacting surfaces of the instrumentalities tends to present a facing to the cementitious mass which will, by merging with this mass, effect a desirable adhesion and prevent the cementitious substance from penetrating 50 into the body of the members. In connection with the fabric-member 9, for instance, it has been found that if the binder—including silicate of soda—penetrates into the body of the fabric, it tends to destroy or 55 disintegrate the threads thereof and, thus, seriously injures it. The sizing prevents this and yet permits the fabric-member to be securely cemented to the paper-member 10. This binder may be in the form of liquid 60 glass, that is, silicate of soda, since this may

be conveniently and quickly applied and dries very rapidly and especially in the presence of heat. Moreover, liquid-glass, when hardened, constitutes an excellent heat-conductor. I have discovered, however, a somewhat different cementitious mass, one which includes flour rendered into proper consistency and combined with a suitable proportion of silicate of soda—and with other substances, preferably, to prevent 70 souring or deterioration of the cement—also constitutes an efficient binder. For my purpose, therefore, it will be understood that I prefer to use either a binder comprising liquid-glass in the commercial form, or one 75 80 which includes silicate of soda combined with other substances.

I prefer to aggroup the members 8, 9 and 10 so as to form the complete device, as an article of manufacture; this including the 85 fabric-member 9 with its ends extended through the slits 11 so they may underlie the opposite ends of the paper-member 8, and with the paper-member 10 interposed between this paper-member 8 and the fabric- 90 member 9. The overlying ends 14 of the paper-member 8 protect the underlying ends 15 of the fabric-member 9. Thus, the opposite ends of the fabric-member are not at all exposed to wear, with the result that when 95 the hosiery is being boarded on the form 1, there is no danger of the fabric-member being injured when the hosiery is stretched down over the form, nor when it is being stripped therefrom. 100

It is to be understood that one of these articles of manufacture, constituting my structure 7, is preferably to be secured to each side of a form by a binder 16, which may be and preferably is the aforementioned 105 cementitious mass used to cement the three members together. In other words, when the device is to be applied to a form, the rear side of the device is coated or painted with the binder 16, and this involves an application of the binder to the rear side of the paper-member 8 and also to the exposed surfaces of the underlying portions 15 of the fabric-member 9. Thus, practically the entire rear surface of the form-adhering member 8 is secured to the side of the form; and, likewise, the portions 15 of the fabric-member are cemented to the form. In consequence, the fabric-member is directly cemented to the form at its ends 15 and is additionally secured thereto by means of the ends of the paper-member 8. 110 115 120

As shown in Figs. 4 and 5 particularly, the binder may be worked up against the edges of the ends of the paper-member 8 so 125 as to form edge-protecting abutments 17. Thus, as shown in Fig. 5 for instance, these abutments form a continuation of the member 8 and reduce the possibility of the stocking being engaged by the edge of the mem- 130

ber 8 and thereby be interfered with in the boarding operation.

In consequence of the fact that the portion 18 of the paper-member 8 which is intermediate of the slits 11 separates the main portion of the fabric-member 9 from the form, this fabric-member does not have the cementitious binder—which is used to secure the device to the form—applied to its effective hosiery-engaging portion, this being prevented by the portion 18 of the paper-member 8. Thus, the member 8 subserves dual functions, namely, to hold in part the fabric-member to the form and, also, in part 15 to separate the fabric-member—at its effective, fabric-engaging portion—from the form. On the other hand, the backing-member 10 separates this effective, fabric-engaging portion of the member 9 from the main 20 portion 18 of the member 8, and also presses the effective, fabric-engaging portion of the member 9 outwardly beyond the plane of the paper-member 8. I wish to be understood, however, that the member 10 may, in some 25 instance, be omitted if desired, in which instance the main portion of the fabric-member would lie against the body-portion of the member 8, instead of being separated therefrom by the member 10 as in the preferred 30 type of the device.

If it be found that this device, as thus constituted, tends to retard the drying operation of the hosiery form, one or all of the three components 8, 9 and 10 may be provided with perforations 19, 20 and 21, respectively, through which the heat may penetrate. These perforations may be variously arranged, be of any required form, and be in 35 staggered or registering relation. Examples 40 of these are shown in Figs. 11 to 16.

From the foregoing, it will be manifest that I have thus provided an effective and durable fabric-holding device which is conveniently and quickly applied to a form—preferably while heated—and one which has the effective portion of the fabric-component separated from the form itself, though having its unexposed ends secured thereto; the aforementioned fabric-engaging 45 portion of the component 9 occupying a plane beyond that of the projecting ends 14 of the member 8 and in a position to perform its designed function of gripping the hosiery and holding it in stretched condition until it is set, after which the hosiery, being then dried, may readily be stripped from the form. Hosiery treated on a form to which my devices are applied has, in practice, been found to have an improved finish, 50 this resulting (in part) from the fact that the device effectively holds the hosiery in intimate contact with the form during the time that the fabric is evaporating its moisture and while being set in the stretched 55 condition into which it has been brought by

the operator. The hosiery thus “finishes” at a uniform length, because it is effectually precluded from creeping or shrinking longitudinally while drying.

What I claim is:—

1. As an article of manufacture, a unitary fabric-holding structure securable to and removable from a drying-form as a unit and including a form-adhering, fabric-protecting member, and a piece of fabric permanently attached thereto and sustainable thereby. 70

2. As an article of manufacture, a fabric-holding structure marketable as a unit and including a form-adhering, fabric-protecting member, and a piece of fabric secured thereto and sustainable thereby; said fabric comprising a body-portion overlying one surface of the member and a pile-portion outstanding therefrom. 80

3. As an article of manufacture, a fabric-holding structure securable to a hosiery drying form and including a form-adhering, fabric-protecting member provided with slots adjacent its opposite edges, and a piece of holding-fabric having its ends projecting through the slots so that they occupy a position on the member at the side thereof opposite the body-portion of the piece whereby the fabric is sustained by the member. 85

4. As an article of manufacture, a fabric-holding structure securable to a hosiery drying form and including a form-adhering, fabric-protecting member provided with slits adjacent its opposite ends, and a piece of holding-fabric having a body-portion extending approximately parallel to one side of the member and its two ends projecting through the slits so as to underlie the opposite side of the member, said member and fabric-piece being sized to effect an intimate 100 adherence between their contacting portions, said fabric-piece including an outstanding pile. 105

5. A fabric-holding structure securable to a hosiery-drying form and including a base-member of asbestos paper containing or impregnated with sizing, and a fabric-engaging fabric coated on one side with sizing and secured to the base-member and having its ends underlying the side of the 110 member opposite to that on which the body-portion of the piece is mounted. 115

6. As an article of manufacture, a fabric-holding structure securable to a drying and shaping form and including a form-adhering member, a section of fabric attached thereto, and an intermediate fabric-distending member. 120

7. As an article of manufacture, a fabric-holding structure securable to a drying and shaping form and including a form-adhering member of paper containing sizing, a section of fabric attached thereto, and an intermediate fabric-distending member also of paper containing sizing. 125

8. A fabric-holding structure securable to a hosiery-form and including a base-member of asbestos paper containing sizing and provided with approximately parallel 5 slits adjacent its opposite ends, a piece of fabric-holding fabric having a pile, one portion thereof overlying the main section of a surface of the base-member and its two ends extending through said slots so as to under-
10 lie the opposite side of the base-member, an intermediate member of asbestos paper containing sizing interposed between the fabric and base-member, and an adhesive between the two members, and between one of the
15 members and the fabric.
9. A hosiery drying and shaping structure including a form, and a fabric-engaging and holding device securable thereto and including a form-adhering
20 member of asbestos paper sized on one side and provided with parallel slots adjacent its ends, a pile-provided fabric attached thereto and extending through the slots so as to have its ends underlie the ends of the form-
25 adhering member and be in contact with the form, a backing-member of asbestos paper

sized on both sides and cemented to the adhering member, and a binder between said member and the form.

10. A hosiery drying and shaping structure including a form, and a fabric-engaging and holding device securable thereto and including a form-adhering member of asbestos paper sized on one side and provided with parallel slots adjacent its 30 ends, a pile-provided fabric attached thereto and extending through the slots so as to have its ends underlie the ends of the form-adhering member and be in contact with the form, a backing-member of asbestos paper 35 sized on both sides and cemented to the adhering member, a binder between said form-adhering member and the form, and a binder also between the form and the ends of the fabric.

In testimony whereof I affix my signature in presence of two witnesses.

JACOB GERRITSON.
